UNITED STATES PATENT OFFICE.

GUIDO FORNACA, OF TURIN, ITALY.

FORCED-FEED INTERNAL-COMBUSTION ENGINE.

Application filed December 18, 1924, Serial No. 756,762, and in Italy December 22, 1923.

This invention relates to forced feed internal combustion engines of the so called V-type, that is, the type in which there are two sets of cylinders arranged in V-form.

5 It has been proposed to construct an engine of this type in which the cylinders are cast integral with the crank case.

The object of the present invention is to simplify the construction of such engines 10 still further, and to the attainment of this object the invention consists in arranging the forced feed compressor between the sets of cylinders and in casting the casing of said compressor in one with the cylinders and 15 with the crank case or the upper part thereof.

The cylinders may have liners separate from the casting which liners may then be made of steel while the casting may be of aluminium so as to obtain an engine of light 20 weight as required for aircraft.

Three examples of engine construction in accordance with the invention are shown on the appended drawing.

Fig. 1 shows (in section) a form in which 25 all the principal parts of the engine are cast in a single piece.

Fig. 2 shows (in section) another form in which liners and cylinder heads are fitted 30 separately.

Fig. 3 shows (in section) a third form in which the lower part of the engine casing is fitted separately.

Referring first more particularly to Fig. 1, 35 the crank casing 1 is cast in one with the cylinders 2, the cylinder jackets 3, the cylinder heads 4, and the body 5 of the forced feed compressor. Access to the interior of the casting for the purpose of machining same is obtained through openings 6 provided in the lower part of the engine casing.

The fitting up of the engine is no more complicated than that of an ordinary engine. The pistons 9 (after the connecting rods 10, 11 have been fitted thereto) are inserted in 45 the cylinders through the openings 6; the crank shaft is inserted through one end of the engine casing provided for that purpose with a suitable cover; the bearing caps of the connecting rods and the main bearing caps are fixed in position through said openings 6; and finally said openings are closed by means of suitable covers.

In the construction illustrated by Fig. 2, 55 the crank casing 2, the cylinder jackets 3, and the compressor body 5 are cast in one

piece as before but the cylinders 8, preferably of special high strength steel, are mounted separately as are the cylinder heads. This construction is without the openings 6 (Fig. 1), because the cylinders, being separate, can be fixed through the cylinder jackets. 60

An arrangement according to Fig. 2 enables very light aluminium alloys to be used for the main casting such as could not be 65 used for the cylinders proper owing to the very high temperatures to which the latter are subjected.

As shown in Figs. 1 and 2 the body or casing 5 of the forced feed compressor is 70 mounted between, and is connected to the two sets of cylinder jackets 3, 3 by webs 12 cast integral with said casing and jackets. The form and arrangement of the webs (only one of which is shown on each side of 75 the casing) are such that they form the sides of conduits for the admission of air to the compressor, the tops and bottoms of said conduits being constituted by the walls of the casing and cylinders respectively. Said 80 conduits are open at their upper ends 13 and converging downwardly communicate at their lower ends with the casing 5, through an opening 14 in the bottom of the latter. 85

Air is drawn through the conduits and through the opening 14 into the bottom of the compressor by the rotation of the compressor blades 15 and operates, during its 90 passage through said conduits as a cooling medium for the cylinders and is therefore supplied to the compressor in a heated condition. The heated compressed air is discharged from the compressor through an opening 16 in the top of the latter and into 95 a conduit 17 in the lower end of which a carburetter 18 discharges. Each conduit 17 has two branch conduits 19 which communicate with the cylinders through the heads 4 as shown in Fig. 1. 100

In the construction illustrated by Fig. 3, the lower part of the crank casing 2' is made and fitted separately with the object of rendering the engine still lighter, as it is possible to make this part, which is not subject to any considerable mechanical strain, of stamped or sheet aluminium. 105

In all cases the carburetter is preferably fitted immediately at the point of delivery of the compressor, so that the compressed 110

air passes directly thereto without passing through long pipes.

What I claim is:

5 A forced feed internal combustion engine of the V-type consisting of a single casting comprising the upper part of the crank case, two cylinders, and the casing for the forced

feed compressor arranged between the two cylinders to which it is connected by means of webs which constitute air inlet conduits 10 to the compressor.

In testimony that I claim the foregoing as my invention, I have signed my name.

GUIDO FORNACA.
